UNITED STATES PATENT OFFICE.

GRANVILLE LEWIS SWENY, OF PIQUA, OHIO.

ANTISKID DEVICE FOR SHOES.

Application filed January 30, 1922. Serial No. 532,538.

To all whom it may concern:

Be it known that I, GRANVILLE LEWIS SWENY, a citizen of the United States, and a resident of Piqua, in the county of Miami 5 and State of Ohio, have invented certain new and useful Improvements in Antiskid Devices for Shoes, of which the following is a specification.

My invention relates to anti-skid or anti-slipping devices for shoes, and it consists in 10 the combinations, constructions and arrangements herein described and claimed.

An object of my invention is to provide 15 an attachment which can be readily applied to or removed from a shoe and which, when in applied position, will engage a surface traversed in such manner as to prevent the slipping of a wearer of the shoe upon a wet or slippery surface.

20 A further object of my invention is to provide an attachment of the character described which is adapted for application to shoes of various sizes and which will engage with a shoe in such manner as to remain 25 thereon without injuring or marring the finish of the shoe.

A still further object of my invention is 30 to provide an attachment of the character described having portions arranged between the shank of the shoe and a surface traversed and exerting a tension on the arch, thereby stiffening the latter and tending to prevent sagging of the shank of the foot of the wearer.

35 A still further object of my invention is to provide an anti-skid or anti-slipping attachment for shoes which will engage the surface traversed with a yielding action, thereby precluding the possibility that 40 shocks and jars may be communicated to the foot of a wearer.

Other objects and advantages will be apparent from the following description, and the novel features of the invention will be 45 particularly outlined in the appended claims.

My invention is illustrated in the accompanying drawings, forming a part of this application, in which:

Fig. 1 is a view showing a shoe equipped 50 with my invention and

Fig. 2 is a bottom plan view of the shoe and attachment shown in Fig. 1.

In carrying out my invention, I make use 55 of a single piece of spring wire which is bent intermediately to provide a loop 1 adapted to embrace the lower part of the

upper of a shoe 2 and to engage with the heel 3 of the shoe at the sides thereof. The sides of the loop 1 are bent vertically into V or U-shaped spring portions 4 and 5 at 60 opposite sides of the heel portion of the shoe, the apex of the spring portion 4 terminating adjacent to the plane of the lower side of the heel and the apex of the spring portion 5 terminating at an appreciable distance 65 above the heel. The sides of the loop are then bent toward each other at 6—6 in underlying relation to the shank portion 7 of the sole of the shoe and contiguous to the front side of the heel 3, meeting at 8 substantially at the longitudinal median line of the shoe and being twisted to extend in twisted relation along the longitudinal median line of the sole of the shoe for an appreciable distance from the front side of 70 the heel. The end portions of the wire are then bent laterally of the twisted-together portions, as at 9—9 and are formed into helical spring portions 10—10 having the largest convolution thereof contiguous to 75 the shank portion of the sole of the shoe at opposite sides of the twisted-together portions and terminating in points 11—11 depending slightly below the plane of the bottom faces of the heel and sole of the shoe. 80

From the foregoing description of the various parts of the device, the operation thereof may be readily understood. The V-shaped spring portions of the loop 1 will yieldingly press against the upper of a shoe and the heel thereof in such manner as to maintain the attachment upon the shoe in the position in which illustrated and to permit of the facile application of the attachment to the shoe. An attachment having a loop of a 90 given size will be suitable for use with shoes of various sizes and to adapt the attachment for use with shoes of even larger or smaller sizes, it is only necessary to vary the angle of divergence of the sides of the V-shaped 100 clamping portions 4 and 5. The ends or points 11 of the helical spring portions 10 will engage with a slippery surface, such as a wet or icy pavement, and will hold the foot of a wearer against slipping, without 105 interfering in any way with the movement of the wearer in walking. Moreover, the shank portion 7 of the shoe will be yieldingly urged upward when the foot is placed upon a flat surface, as in walking, thereby precluding the sagging of the arch of the shoe 110 and extending the life of the shoe in service.

beyond that of a shoe not equipped with my invention, while beneficially bracing the foot of a wearer of the shoe.

Obviously, my invention is susceptible of embodiment in forms other than that in which illustrated in the accompanying drawings and described herein, and I therefore consider as my own, all modifications and adaptations of the form of the device disclosed herein which fairly fall within the scope of the appended claims.

I claim:—

1. A device of the character described comprising a helical spring portion terminating at its smaller end in a point, and means for releasably securing the helical spring portion to the bottom of a shoe to position the larger end of the helical spring portion in underlying relation to the bottom 20 of the shoe and the point of the helical spring portion in a plane below the plane of the sole of the shoe.

2. A device of the character described comprising a pair of helical spring portions, 25 each terminating at its smaller end in a point, and means connecting with the larger end of said helical portion for releasably securing the latter to a shoe in such manner as to position the larger end of the helical 30 portion in contiguity to the shank portion of the sole of the shoe, the helical portion being of such length that the point thereof depends below the plane of the sole of the shoe.

3. The combination with a shoe, of a demountable attachment therefor, said attachment comprising a loop portion embracing the shoe at the sides of the heel and above the heel thereof, and helical spring portions 40 carried by said loop in advance of the heel with the larger ends thereof contiguous to the lower side of the shank portion of the sole of the shoe and the smaller ends of the helical portions terminating below the plane 45 of the heel of the shoe.

4. As an article of manufacture, an anti-skid device for shoes made of a single piece of spring wire bent intermediately to form a loop adapted to embrace the heel portion 50 of a shoe so that the sides of the loop meet contiguous to the front side of the heel substantially in the longitudinal median line of the shoe, said sides being twisted together and the end portions thereof then being 55 bent into helical spring portions terminating in points extending below the plane of the heel.

5. As an article of manufacture, an anti-skid device for shoes made of a single piece 60 of spring wire bent intermediately to form a loop adapted to embrace the heel portion of a shoe so that the sides of the loop meet contiguous to the front side of the heel substantially in the longitudinal median line

of the shoe, said sides being twisted together 65 and the end portions thereof then being bent into helical spring portions terminating in points extending below the plane of the heel, the axes of said helical portions being substantially vertical. 70

6. As an article of manufacture, an anti-skid device for shoes comprising a single piece of spring wire having the end portions thereof formed into helical spring portions having their axes substantially parallel and 75 terminating at the smaller ends thereof in points, the portion of said piece of spring wire between the helical spring portions being formed to provide means for securing the helical spring portions to the under side 80 of the shank portion of a shoe, with the axes of said helical portions substantially perpendicular.

7. As an article of manufacture, an anti-skid device for shoes formed of a single 85 piece of spring wire bent intermediately into a loop portion adapted to embrace the heel portion of a shoe, the sides of said loop being bent toward each other and twisted together at a distance from the end thereof, the end 90 portions of the spring wire being formed into a pair of helical spring portions disposed at opposite sides of the twisted together portions and terminating in points.

8. As an article of manufacture, an anti-skid device comprising a single piece of 95 spring wire formed to provide helical spring portions at the ends thereof, a loop portion intermediate of the ends of the spring wire and adapted to embrace the heel portion of 100 a shoe, and a connecting portion merging the loop portion into the helical spring portions.

9. As an article of manufacture, an anti-skid device comprising a single piece of 105 spring wire formed to provide helical spring portions at the ends thereof, a loop portion intermediate of the ends of the spring wire and adapted to embrace the heel portion of a shoe, and a connecting portion merging the loop portion into the helical spring 110 portions, the axes of said helical portions being parallel and the sides of said loop portion being bent in the direction of the axes of the helical portions to provide V-shaped spring portions. 115

10. As an article of manufacture, an anti-skid device comprising a single piece of spring wire formed to provide helical spring portions at the ends thereof, a loop portion intermediate of the ends of the spring wire and adapted to embrace the heel portion of a shoe, and a connecting portion merging the loop portion into the helical spring portions, said connecting portion comprising 120 twisted together portions of the sides of the loop portion.

GRANVILLE LEWIS SWENY.
